UNITED STATES PATENT OFFICE.

PHILIP LANE SCOTT, OF CHICAGO, ILLINOIS, ASSIGNOR TO SUPER-DIESEL TRACTOR CORPORATION, OF LA PORTE, INDIANA, A CORPORATION OF NEW YORK.

RELIEF MECHANISM FOR FUEL-INJECTION SYSTEMS.

Continuation of application Serial No. 240,706, filed January 18, 1918. This application filed August 15, 1921. Serial No. 492,596.

This application is a continuation of my application filed on January 18, 1918 under Serial Number 240,706 and described my invention which relates to improvements in pumps adapted particularly for injecting liquid fuel at high pressure into the working cylinder of an internal combustion engine, where the fuel is ignited by the high temperature of a charge of air that has previously been admitted to the cylinder and compressed to a high degree during the compression stroke of the engine. The liquid fuel is supplied to the cylinder through a spray valve and with the types of pumps at present in use the rate of injection of the fuel decreases rapidly toward the end of the pump stroke, and the amount of fuel delivered is so small that there is a tendency for drops to ooze out at the end of the pumping stroke due to residual pressure in the pump chamber. These drops may either burn at the end of the injection period just completed or may remain on the nozzle until the next injection period when they will be carried forward as drops with the new fuel charge. In either case there is combustion in the relative liquid from these drops.

It is an object of the present invention to provide, in connection with the mechanism for operating the pump plunger or piston, an arrangement such that the plunger will be disengaged from its actuating mechanism as it approaches the limit of its working stroke, and quickly returned to the position it occupies at the beginning of the stroke. This quick release of the pump plunger will cause a sudden diminution of pressure in the passage way leading to the valve and in the pump chamber which controls the admission of fuel to the cylinder, and this valve will close suddenly due to this reduction in pressure to cut off the fuel and prevent it from dripping into the cylinder.

The particular nature of the present invention will appear more clearly from a description of a preferred embodiment thereof as shown in the accompanying drawing in which:

Figure 1 is an elevation chiefly in section, Figure 2 is a plan view with a portion of the housing of the mechanism broken away.

Referring to the drawings in which

similar reference characters denote similar parts in each of the figures, 10 designates the casing or body of a fuel pump which may be of any preferred construction. Attached to the pump casing is a housing 11 which carries the mechanism of the present invention. The portion of the housing adjacent the pump casing is provided with a bore within which extends the outer end of the pump plunger 12, the latter being provided with an enlarged end 13 surrounded by a head 14 which forms an abutment for one end of the spring 15, the other end of which is placed around a post 16 projecting from the end of the pump casing. A guiding cap 17 is slidably mounted in the bore of the housing 11 and engages the end of the pump plunger. A roller 18 contacts with the end of the cap 17, and this roller is mounted on a lever 19 which is pivoted to a shaft 20 supported in bearings 21 projecting from the inner walls of the housing.

An arm 22 within the housing is provided with a rolling surface adapted to engage the outer edge of lever 19, and this arm 22 is attached to a shaft 23 mounted in bearings 24 projecting from the inside of the walls of the housing. One end of shaft 23 is extended through the housing, and to this end is attached an arm 25 having a forked upper end 26 to receive rod 27 which is connected in any desired manner to a part of the engine adapted to reciprocate this rod. A plate 28, preferably formed of hardened steel, is attached to the lower face of rod 27, and normally makes contact with the upper edge of arm 25. The lower face of the arm 27 is provided with an inclined or cam face 28 adapted when the rod 27 is moved toward the pump to engage the nose of a set screw 30 mounted in a bracket 31 formed on the outside of the housing.

The operation of the mechanism described above is as follows:

The rod 27 is reciprocated from a moving part of the engine, and assuming that it starts from the position shown in Fig. 1, with the plate 28 engaging the upper end of arm 25, this arm will be rotated and likewise the arm 22. The curved face of the latter will make a rolling contact with the lever 19 moving the latter inwardly and through the roller 18 and cap 17 will cause the pump plunger 12 to make its working

stroke. As soon, however, as the cam face 29 engages the nose of set screw 30, the rod 27 will be lifted sufficiently to release plate 28 from the upper end of the arm 25, but 5 the rod will be retained in place within the forked end of this arm. As soon as the actuating rod 27 has been disengaged from the arm 25, the spring 15 which was put under compression during the working 10 stroke of the pump will quickly restore the pump plunger, lever 19 and arms 22 and 25 to their outward position, thus causing a sudden release of the pressure in the pump chamber. This sudden release of pressure 15 will permit a quick closure of the valve controlling the admission of fuel into the engine cylinder to cut off the fuel and prevent it from dripping into the cylinder. As soon as the reciprocating rod has been moved outwardly 20 far enough for the plate 28 to again engage the upper end of the arm 25, the mechanism will be restored to condition for a subsequent operation.

Some pumps of the general type used for 25 injecting liquid fuel into the cylinder of an internal combustion engine under high pressure are provided with a discharge valve communicating with the pump chamber and through which the fuel passes before going 30 to the passageway leading to the spray valve, but with the quick relief mechanism of the present invention, the sudden diminution of pressure in the pump chamber caused by the quick release of the pump plunger 35 would cause the discharge valve to close immediately thereby preventing the diminution of pressure from extending to the spray valve and defeating the purpose of this invention. This defect may be avoided by 40 removing the discharge valve from the fuel pump and allowing the spray valve to control the admission of fuel from the pump chamber to the engine cylinder or any suitable construction may be provided for holding 45 the discharge valve open at the instant when the pressure in the system is to be relieved.

It will also be understood that various 50 changes in the details of construction may be made without departing from the principle of the invention.

I have spoken of the sudden release of 55 pressure in the fuel line which permits a quick closure of the valve controlling admission of the fuel and prevents the formation 60 of drops at the spray valve. This sudden pressure release which is due to the sudden withdrawal of the pump plunger sets up a negative pressure at all parts in the injection system between the injection valve and the spray valve. If the drives are positive 65 mechanical drives with all members at all times joined to permit motion in either direction, the return movement of the pump plunger would accomplish solid pressure re-

lease in the system before drops have a chance to form due to the residual pressure from the injection stroke just preceding, that is, all eccentric or cam forms normally used prevent a sudden pressure release due 70 to the inability to get sufficient high acceleration in the reverse direction without straining the mechanism.

If, however, some member of the driving 75 linkage can be suddenly thrown out of operation, that is if the drive is not an opposite drive in both directions, such member can be disconnected and at the instant of its disconnection if a spring opposed to the 80 operation of the driving linkage, this spring will impart to the pump plunger very rapid acceleration in the opposite direction to its pumping stroke producing a very sudden diminution in the injection pressure, so sudden 85 that drops will not have time to form.

I claim:

1. In a pump for supplying fuel to the combustion chamber of an internal combustion engine, a pump plunger, a lever for actuating said plunger, an arm engaging said lever, a second arm associated with the first arm, a reciprocating rod actuated by the moving parts of the engine and normally 90 engaging said second arm to rotate the arm and through the first arm and lever actuate 95 the pump plunger, means for disengaging said rod from said second arm as the pump plunger approaches the end of its working stroke and a spring for quickly withdrawing 100 said plunger to relieve the injection pressure when said rod is disengaged from said second arm.

2. In a pump supplying fuel to the combustion chamber of an internal combustion engine, a pump plunger, a lever for actuating said plunger, an arm engaging the lever, a second arm operatively connected to said first arm, a reciprocating rod actuated by the moving parts of the engine and normally 105 engaging the end of said second arm and adapted through said second arm, said first arm and said lever to cause the pump plunger 110 to effect a working stroke, said rod being provided with a cam face, a set screw adapted to co-act with the cam face of the rod to lift the rod out of engagement with said second arm, said set screw and cam face being so related that the rod is disengaged 115 from the second arm when the pump plunger approaches the end of its working stroke, and means for quickly withdrawing said plunger to relieve the injection pressure when said rod is lifted out of engagement with said second arm.

3. In a pump for supplying fuel to the combustion chamber of an internal combustion engine, a pump plunger adapted to reciprocate in the chamber of the pump, a spring for normally withdrawing the plunger from the pump chamber, a slid- 125 130

- member normally engaging the outer end of the plunger, a lever provided with a roller adapted to engage the slideable member, an arm provided with a curved face 5 adapted to engage an edge of the lever, a shaft to which said arm is attached, a second arm attached to said shaft and provided with a slotted extremity, a reciprocating rod within said extremity and having a plate 10 of hardened material adapted to engage the upper end of said arm, so that when said rod is actuated by a moving part of the engine, it will through said arms, lever, and slideable member compress said spring and cause said 15 plunger to make a working stroke, said reciprocating rod being provided with a cam surface on its under face, and a set screw adapted to be engaged by the cam face on said rod at the end of the pump stroke to 20 lift the rod and disengage the plate from the end of said second arm to permit said spring to force the pump outward to cause a sudden release of pressure in the pump chamber and fuel passages communicating therewith, substantially as described. 25
4. In a pump for supplying fuel to the combustion chamber of an internal combustion engine, a pump plunger, a lever for actuating the plunger, means mounted
- adjacent to the lever for swinging the same, 30 a reciprocating rod actuated by the moving parts of the engine and normally engaging said means to move the same and swing the lever, means for disengaging the rod from said means as the pump plunger approaches 35 the end of its working stroke, and means for quickly withdrawing the plunger to relieve the injection pressure when the rod is disengaged from the means. 40
5. In a pump for supplying fuel to the combustion chamber of an internal combustion engine, a pump plunger, a spring arranged to move the plunger on its suction stroke, mechanism for moving the plunger on the injection stroke against the action of 45 the spring, comprising a lever and a reciprocating rod actuated by the moving parts of the engine and operatively connected to the lever during this stroke, and means for swinging the rod out of operative relation 50 to the lever near the end of the injection stroke to permit the spring suddenly to withdraw the plunger and relieve the injection pressure. 55

Signed at Chicago county of Cook and State of Illinois, this 13th day of August, 1921.

PHILIP LANE SCOTT.
